UNITED STATES PATENT OFFICE.

EUGENE N. STROM, OF CHICAGO, ILLINOIS, ASSIGNOR TO PETTIBONE MULLIKEN COMPANY, OF CHICAGO, ILLINOIS, A CORPORATION OF ILLINOIS.

CAST-METAL RAILWAY-CROSSING.

1,121,305.

Specification of Letters Patent.

Patented Dec. 15, 1914.

Application filed October 17, 1914. Serial No. 867,106.

To all whom it may concern:

Be it known that I, EUGENE N. STROM, a citizen of the United States, residing at Chicago, in the county of Cook and State of Illinois, have invented a new and useful Improvement in Cast-Metal Railway-Crossings, of which the following is a specification.

My invention relates to the class of cast-metal railway-crossings.

The tendency in crossings of the kind to which the present improvement relates is to break adjacent to the intersections of the wheel-flange grooves under the blows and stresses exerted by the wheels at these intersections in traversing the crossing.

The primary object of my improvement is to reinforce these intersections against such breaking, especially at the angle there-20 of which is subject to wheel-pounding most frequently in the use of the crossing; and it is my further object to reinforce against cracking, in the cooling of the casting, the extensions of the crossing at the rectangular 25 offsets where the main rails of the track are fitted laterally against and spliced to the extensions.

In the accompanying drawings, Figure 1 is a plan view showing one of the four corner or intersecting portions of a rectangular cast-metal railway-crossing; Fig. 1^a is a plan section taken just below the treads in Fig. 1, and Figs. 2, 3 and 4 are enlarged sections on lines 2, 3 and 4, Fig. 1, respectively, 35 though in Fig. 4 is shown the fish-plate for splicing the main rail to an arm of the crossing, omitted in Fig. 1 to avoid confusion.

Only one corner-portion of the crossing is shown in the drawings, to enable it to be 40 illustrated on an adequately large scale and to avoid unnecessary multiplication of the showing. It will be understood, however, that the other three corner-portions are like that shown, and that two may be provided 45 as an integral casting, two of such pairs forming halves of the crossing, being united by fish-plates, which is common practice in this art.

The tread-portions 5 having the vertical 50 side-walls 6 provided with base-flanges 7, contain the usual wheel-flange grooves 8 that intersect each other at the central part of the casting. The point in the intersection of the grooves 8 which is subjected to 55 most of the pounding by the wheel-treads of

trains traversing the crossing is at 8^a. That is to say, with a succession of trains running from left to right and the same number running from right to left, Fig. 1, the point 8^a and the opposite point in line with it will each receive the same number of blows, the number of wheels being the same on each train; and with the same number of trains, in the same condition as to number of wheels, running in opposite directions in the direction 60 at right angles to that first described, the point 8^a will receive the same number of blows. Obviously, therefore, for each blow against each of the two other points, the point 8^a is subjected to two blows; and thus the 65 crossing is subjected to the greatest strains of the wheels traversing it at its four points 8^a, and requires there the greatest reinforcement. To thus reinforce it, I cast on the under faces of the treads 5 extending at 70 right angles to each other with relation to the point 8^a and intermediately of and parallel with the respective side-walls of those treads, a substantial depending rib 9 to bring the apex of the angle it forms coincident with the angle at 8^a; and between that angle and the adjacent diagonally opposite angle of the outer diverging side-walls of the structure, I cast on the lower parts of the rib and those meeting walls a horizontal 75 web 10. Thus, the force of the wheel-blows against the point 8^a is taken and distributed through the medium of the rib 9 and the diagonal web 10 over the adjacent parts of the crossing-structure, thereby shielding it 80 against fracture at the grooved portion thereof adjacent to the aforesaid point.

To reinforce the structure along each of its four divergent arms, I cast horizontal webs 11 on the opposite side-walls 6 along 95 the bases of those arms of the crossing, and vertical webs 11^a at intervals connecting the horizontal webs with the bottom face of the tread. These horizontal webs might be continuous along the base of each arm, were 100 it not for the necessity of discharging the core-sand used in casting, for effecting which discharge, openings 12 are provided between the webs 11. These webs 11 and 11^a take the strains exerted by the wheel-flanges 105 against the sides of the grooves 8 and distribute them over the structure, thus shielding it against fracture.

Other weak places in a cast railway-crossing are at the points 13 where main rails, 110

like the rail shown at 14 in Figs. 1 and 4, are spliced, each by a fish-plate 15 (Fig. 4), to an arm of the crossing. At these points, or angles, which are formed by rectangular offsets in the arms, the casting tends, in cooling, to crack in a diagonal direction. To there reinforce it, I cast on the under sides of the tread-portions of those arms, ribs 9^a, which are shown as and may be continuations of the rib 9, though in that case the sections 9^a should be offset at 9^b and again at 9^c to extend along the inner sides of the webs of the main rails 14 and fit against the latter and between their heads and base-flanges, as will be clear from the representation in Fig. 4. Reinforcing webs 11 connect the lower parts of the ribs 9^a with the adjacent vertical walls 6 of the divergent arms at intervals, but the vertical webs 11^a are omitted, as being unnecessary, along the ribs 9^a.

What I claim as new and desire to secure by Letters Patent is:

1. A hollow cast-metal railway-crossing having divergent arms forming treads provided with intersecting wheel-flange grooves and side-walls, an angular reinforcing rib on the under faces of the treads of adjacent diverging arms of the structure located between the vertical walls, having its angle coincident with that formed by the intersecting wheel-flange grooves, and a web connecting said rib and the vertical walls at said angles.

2. A hollow cast-metal railway-crossing having divergent arms forming treads provided with intersecting wheel-flange grooves

and side-walls, an angular reinforcing rib on the under faces of the treads of adjacent diverging arms of the structure located between the vertical walls, having its angle coincident with that formed by the intersecting wheel-flange grooves, and a flat, horizontal diagonally extending web connecting said rib and walls at said angle.

3. A hollow cast-metal railway-crossing having divergent arms provided with rectangular offsets at which to splice main rails, ribs cast on the under faces of the tread-portions of the offset-sections of said arms and extending across said offsets, and horizontal webs cast integral with and connecting said ribs and the adjacent vertical walls of said arms at intervals.

4. A hollow cast-metal railway-crossing having divergent arms forming treads provided with intersecting wheel-flange grooves and side-walls, and provided with rectangular offsets at which to splice main rails, an angular reinforcing rib cast on the under faces of the treads of adjacent arms, extending across said offsets and provided with offsets in the extended sections, said rib having its angle coincident with that formed by the meeting of said walls, a web connecting said rib and walls at their adjacent said angles, and webs cast integral with and extending at intervals along said rib and the bottom of said arms.

EUGENE N. STROM.
